UNITED STATES PATENT OFFICE

GUSTAV JANSSON, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

INSULATOR

Application filed February 23, 1926. Serial No. 89,889.

This invention relates to bushings which are used to insulate incoming and outgoing high tension leads for electrical apparatus, as electric switches, and has particular reference to bushings of the solid type which comprises two or more concentric tubes of insulating material, as porcelain.

In an insulating bushing of the type above set forth, when used with an electric switch, a massive conducting rod or stud is extended through and is supported by the bushing and bears a contact block at its lower end, and, usually, a screw-threaded terminal-connector at its upper end.

One of the objects of this invention is the provision of means to lock the stud against rotation in and to the bushing, thereby to prevent change in alignment between the contact members carried by the lower end of the stud and the movable contact members of the switch.

The conducting stud is adapted to heat and expand when conducting a heavy current. Since the coefficients of expansion of porcelain and of the stud are much different, and the heating is originated in the stud, it is a further object to connect the stud rigidly with the insulator only at one point, so that the stud is free to expand without applying any material stress to the insulator.

An insulating bushing used for electric switches is subject to substantial pressure and impacts at its lower end, due to the action of the movable contact members, as the switch is operated. With the usual construction of multi-tube solid bushings the arrangement, and the manner of bonding the tubes together, has been such that the stresses in the tubes, resulting from the operation of the switch, have been largely tension stresses. Porcelain is relatively weak to resist tension forces and especially suddenly-applied, or impact, tension forces, and consequently may fail mechanically.

Porcelain, however, is relatively strong to resist compression forces, even though suddenly applied.

Consequently, a further object of this invention is the provision of a multi-tube bushing so constructed and arranged that the im-

portant parts thereof are mainly under compression when subjected to the forces and shocks incident to switching operations.

A further object is the provision of a multibular insulator having petticoats or corrugations and so arranged as to facilitate the assembly of the various parts.

A further object of the invention is generally to improve the construction and performance of insulating bushings.

The structure of the insulator with which this invention is particularly concerned is described but not claimed in my co-pending application Serial No. 89,888, filed February 23, 1926, which issued as Patent No. 1,816, 65 852, dated August 4, 1931.

Fig. 1 is a side elevation partly in section of an electric insulator embodying the invention.

Fig. 2 is a detail illustrating the arrangement of arcing members on the lower end of the insulator of Fig. 1.

As here shown, the insulator embodying my invention includes two concentric porcelain tubes 10 and 12 of substantial length, open at both ends, and spaced apart so as to form an interposed annular space or compartment 14, which space may be approximately co-extensive with the length of said outer tube 12 and may have a relatively small cross sectional dimension. Said space may be filled with some loose granular material, such as crushed porcelain, to improve the specific inductive capacity of said space and reduce losses therein, as set forth in my above named co-pending application.

An annular metal flange 16 is disposed about the outer tube 12 intermediate the ends thereof, and said flange is secured fixedly to said tube by any suitable means, as a body of cement 18. Annular grooves 20 are provided in the vertical face of said flange 16 to receive cement whereby to strengthen the bond between said flange and said cement. Said flange is secured by bolts 24 to the casting 22 of any suitable electrical apparatus as an electric switch.

A body of cement 42 is provided to unite the tubes rigidly together at their lower ends and also to form a bottom closure for the

space 14. The effectiveness of the cement bond is increased by staggered annular grooves 44 formed in the proximate faces of the tube walls at this point and adapted to be occupied by the cement.

Said inner tube is provided at its lower end with an enlarged annular recess 28 adapted to receive the metal bushing 30, and a body of cement 32 between the bushing and 10 said inner tube secures said bushing fixedly in position in said tube so that the inner passage of the bushing is aligned with the axial passage in the tube 10. Said bushing is provided with an integral outstanding annular 15 flange 34 which is adapted to bear against the end of said tube and receive any pressure exerted against the bushing.

A conductor or stud 36 is disposed within the axial passage 38 of said tube 10 and is 20 screw-threaded at its lower end into the bushing 30 and is arranged to extend a substantial distance below the bushing to provide the externally screw-threaded portion 40.

When the bushing is employed as the terminal of an electric switch, for which use it is especially adapted, a contact block 41 is screw-threaded onto said portion 40 of the conductor-stud and is provided with the lower contact surface 43 against which the 25 main movable contact member 44 is adapted to bear. Said block is also provided with the spaced depending arcing members 45. Said contact block 41 is arranged to be held in fixed relation with the conductor-stud by 30 means of some suitable clamping device, as the lock nut 47, which is adapted to secure it from turning on said conductor rod 36 after said fixed contact member is aligned with its cooperating movable contact member.

40 A metal ferrule 46 is fixed to the upper end of the outer tube 12 by a body of cement 48 or other suitable attaching means, and extends over and provides a closure for the top openings of both tubes 10 and 12. Said ferrule is also provided with the integral up-standing neck 50 which is arranged to receive said conductor 36 in the central opening 52 thereof. An axially extended slot 54 provided in said conductor 36 and a corresponding slot 56 in the adjacent neck 50 are adapted to receive a spline 58 whereby to prevent rotation of said conductor within said neck, thus preserving the alignment of the contact block 41 with its cooperating 45 movable switch member. One of said slots, as the slot 54 is arranged to be sufficiently longer than said spline to permit free vertical, or axial, movement of said conductor.

60 A yielding packing 60 of suitable insulating material may be interposed between the ferrule 46 and the top of the inner tube 10 to provide a yielding cushion against which said inner tube may expand.

65 The conductor 36 extends through and beyond the end of the ferrule 46 and is screw-

threaded into the metal terminal connector 62. Said connector is provided with an externally screw-threaded stud 64 to which a line conductor is adapted to be attached, and said connector is also provided with a depending 70 annular apron or flange 66 which surrounds the neck 50 of said ferrule and is arranged in covering relation with the conductor-passage in said neck. Said apron is free to move axially under the expansion and contraction 75 of the conductor, while maintaining the aforesaid relation.

Said insulating tubes 10 and 12 are provided with annular corrugations 68 at their lower ends for the purpose of increasing the 80 surface leakage path around the end of the insulator. The lower corrugated end of said inner tube is extended below the lower end of said outer tube, and is enlarged at its lower end, whereby to enhance the length of the 85 leakage path over the corrugations. The upper end of said outer tube 12 is provided with a series of petticoat flanges 70 extending from its top to the supporting flange 16. It 90 will be noticed that the inner tube is practically free from any irregularities throughout the major portion of its length, all of the flanges or petticoats being carried by the outer tube 12, so that the manufacture 95 of the inner tubes and the assembly of the insulator is simplified over the usual insulators of this type.

By reason of the bonding of the insulating tubes at their lower ends, a pressure exerted 100 upwardly on the lower end of the inner tube is transmitted through the inner tube to the cement which bonds it to the outer tube and thence by way of the outer tube to the supporting flange of the insulator thus placing 105 both tubes under compression. Porcelain is relatively weak under tension, while it is relatively strong in compression. By the provisions of this invention, any stress acting upwardly against the end of the insulator will be transmitted as a compression 110 stress through a comparatively short length of the insulator. That portion of the outer insulator above the supporting flange 16 and that part of the inner insulator above the cement 42 will be unstressed. This is a distinct 115 improvement over the heretofore customary construction wherein the insulator is subjected to tension stresses, and is stressed throughout its entire length.

The construction may be otherwise modified without departing from the spirit of the invention.

I claim:

1. In an electric insulator, the combination of an outer insulating tube having a series of integral petticoats, an inner insulating tube having straight tubular walls, co-extensive with the length of said outer tube and an enlarged externally corrugated section disposed below the lower end of said 125 130

- outer tube, a metal cap overlying the upper ends of said tubes, and attached to said outer tube only, and an attaching flange connected with said outer tube intermediate its ends.
- 5 2. In an insulator, the combination of two concentric tubes of insulating material having an annular space between them, a supporting flange carried by said outer tube intermediate its ends, an axial conductor disposed within the inner tube and rigidly af-
fixed thereto at its lower end only and hav-
ing its upper end in sliding engagement with
the insulator, and a body of cement secur-
ing said tubes firmly together at their lower
10 ends only.
- 15 3. In an electric insulator, the combination of inner and outer insulating tubes open at both ends and having an intervening space, a metal cap disposed over the upper ends of said tubes and fixed to said outer tube, an axial conductor disposed within said inner tube and passing through said cap, and a key
cooperating between said cap and said con-
ductor to prevent turning of said conductor
20 within said tubes while permitting free axial
movement through said cap.
- 25 4. In an electric insulator, the combination of spaced concentric insulating tubes having means rigidly connecting their lower ends only, an axial conductor disposed within the inner tube, and a metal bushing having an outstanding flange screw-threaded to the end of said conductor and disposed within a recess in the lower end of and fixed to said
30 inner tube, said flange having a bearing
against the end of said inner tube.
- 35 5. In an electric insulator, the combination of two spaced concentric tubes of insulating material having means rigidly connecting their lower ends, a supporting flange carried by said outer tube intermediate its ends, a conductor disposed within said inner tube and fixed thereto at its lower end, a metal ferrule disposed over the tops of
40 said tubes to form a closure for the upper ends thereof and secured fixedly to said outer tube, and means connecting said con-
ductor and said metal ferrule to restrain
45 said conductor against rotation while per-
mitting it to move lengthwise therein.
- 50 6. An electric insulator comprising an insulating tube open at the top, a ferrule carried by the upper end of said tube and pro-
viding a cover therefor, said ferrule having
55 an upstanding neck, a conductor passed free-
ly through and arranged for axial move-
ments in said neck due to expansion and
contraction, and a cap carried by said con-
ductor having a depending side wall which
60 surrounds said neck and is free to move there-
over following movements of said conductor
while preserving its surrounding relation
with said neck.
- 65 7. An insulator having the combination of
two insulating tubes, one contained within
the other, and having a rigid connection be-
tween them at their lower ends only, said
tubes being otherwise free from positive con-
nection and being free to expand independ-
ently, a relatively rigid conductor extended
70 through said inner tube and having a rigid
connection with the insulator only at the
lower end of said inner tube, and being other-
wise free from rigid connection with the
insulator.
- 75 8. An insulating bushing including the
combination of an outer insulating shell, an
inner insulating tube, and a rigid conducting
stud extended through said insulating tube,
said insulating tube having means support-
ing it in said shell which provides for free
longitudinal expansion and contraction
thereof and said conducting stud having a
support on said inner tube only at its lower
80 end and having a sliding engagement with
said bushing at its upper end whereby it can
freely expand and contract longitudinally.
- 85 9. An insulating bushing including the
combination of an outer insulating shell, an
inner insulating tube and a rigid conducting
stud extended through said insulating tube,
said insulating tube having means support-
ing it in said shell which provides for free
longitudinal expansion and contraction
thereof and said conducting stud having a
connection with said bushing only at the
lower end of said inner insulating tube and
being otherwise free from a positive restraining
connection with said bushing and hav-
ing a sliding engagement with said bushing
90 at its upper end, whereby said stud is free
to expand and contract longitudinally.
- 95 10. In an electric insulator, the combina-
tion of an outer insulating tube which has a
series of petticoats thereon, an inner insulat-
ing tube which has a straight tubular wall
100 which lies within and extends lengthwise
of said outer tube for at least the major
portion of its length and has an enlarged
externally-corrugated section which is dis-
posed below and overlies the lower end of
105 said outer tube, a metal cap which overlies
the upper ends of said tubes and has a
weather-proof connection with said outer
tube, and an attaching flange connected with
110 said outer tube intermediate its ends.
11. In an electric insulator, the combina-
tion of an outer insulating tube which has a
series of petticoats thereon, an inner insulat-
ing tube which has a straight tubular wall
115 which lies within and extends lengthwise
of said outer tube for at least the major portion
of its length and has an enlarged externally-
corrugated section which is disposed below
120 and overlies the lower end of said outer tube,
a metal cap which overlies the upper ends of
said tubes and has a weather-proof connec-
tion with said outer tube, an attaching flange
125 connected with said outer tube intermediate
its ends, and means securing the lower ends
130

of said two tubes in the aforesaid relation.

12. In an electric insulator, the combination of an outer insulating tube which is open at both ends, an inner insulating tube which is open at both ends and has a straight side wall which is located within and overlies the major part of the inner face of said outer tube and has an enlarged lower portion which is located below and overlies the lower end 5 of said outer tube, a metal cap which overlies the upper ends of said tubes and constitutes a closure therefor and has a weather-proof connection with said outer tube, a metal member which overlies the lower end of said inner tube, and a stud which extends through said tubes and has a connection both with said cap and member.

13. An electric insulating bushing consisting of the combination of a straight outer insulating tube having an outstanding metal attaching flange fixed thereto intermediate its ends, a straight inner insulating tube located within said outer tube having its upper end terminated below the upper end of said outer 20 tube and its lower end extended downwardly below the lower end of said outer tube and having an enlarged lower end which is located below and overlies the lower end of said outer tube and a connection with the lower end of said outer tube by which an upward thrust on the lower end of said tube is transmitted to the lower end of said outer tube, a metal cap overlying the upper ends of both tubes and constituting a closure there- 25 for and having a weather-proof connection with the upper end of said outer tube, and a stud extended through said cap and said tubes and having a pressure-bearing on the lower end of said inner tube, the connections 30 between the lower ends of said tubes, and between said stud and the lower end of said inner tube being such that both tubes are placed only in compression between the lower ends thereof and said attaching flange when 35 the lower end of said inner tube is subjected to an upward thrust.

14. An insulating bushing comprising an outer insulating tube having an attaching flange intermediate its ends, an inner insulating tube which is located within said outer tube except at the bottom thereof where it projects below said outer tube and has an enlarged lower end that is too large to pass into said outer tube, a metal cap overlying 50 the top of said outer tube, a bearing member overlying the enlarged lower end of said inner tube, and a conducting stud extended through said inner tube and said metal cap and said bearing member.

15. In an electric insulator, the combination of an insulating tube, a conducting stud disposed within said tube, means located at one end of said tube which rigidly connects one end only of said stud with said end of 55 said tube against axial movement relative to

said end of said tube, the other end of said stud being free for axial movement relatively to the other end of said tube, means located at the free end of said stud which connects it slidingly with said tube and locks said 70 stud against rotation relative to said tube, and terminals at the ends of said tube having connections with the fixed and free ends of said stud, the terminal at the free end of said stud having a threaded connection there- 75 with.

In testimony whereof, I have signed my name to this specification.

GUSTAV JANSSON.
